GARMENT FOR HOLDING A DIAPER

George F. Koury, Metairie, La., assignor to Pantasote
Company, New York, N.Y.

Filed Mar. 10, 1972, Ser. No. 233,865

Term of patent 14 years

Int. Cl. D2—01; D24—04
U.S. Cl. D83—1 A

FIG. 1 is a top plan view of a garment, formed of flexible sheet material such as flexible translucent plastic sheet material, embodying my new design;

FIG. 2 is a side edge view;

FIG. 3 is an end edge view from line 3—3 of FIG. 1;

FIG. 4 is a bottom plan view;

FIG. 5 is a section along line 5—5 of FIG. 1 and to a larger scale than FIG. 1;

FIG. 6 is a section along line 6—6 of FIG. 1 and to a larger scale than FIG. 1; and

FIG. 7 is a section along line 7—7 of FIG. 1 and to the scale of FIG. 6.

I claim:

The ornamental design for a garment for holding a diaper, substantially as shown and described.
